US0D1061516S

(12) **United States Design Patent** (10) **Patent No.:** **US D1,061,516 S**
(45) **Date of Patent:** **** Feb. 11, 2025**

(54) **SMART WATCH**

(71) Applicant: **BEIJING XIAOMI MOBILE SOFTWARE CO., LTD.**, Beijing (CN)
(72) Inventor: **Jingfan Jiang**, Beijing (CN)
(73) Assignee: **BEIJING XIAOMI MOBILE SOFTWARE CO., LTD.**, Beijing (CN)

(**) Term: **15 Years**

(21) Appl. No.: **35/517,417**

(22) Filed: **Feb. 8, 2023**

(80) **Hague Agreement Data**

Int. Filing Date: **Feb. 8, 2023**

Int. Reg. No.: **DM/229127**

Int. Reg. Date: **Feb. 8, 2023**

Int. Reg. Pub. Date: **Jun. 2, 2023**

(30) **Foreign Application Priority Data**

Aug. 9, 2022 (CN) 202230518034.5
